(57) **CLAIM**

The ornamental design for a resistor, as shown and described.

DESCRIPTION

FIG. 1 is a front, left-side, top perspective view of the resistor;

FIG. 2 is a front elevational view thereof;

FIG. 3 is a rear elevational view thereof;

FIG. 4 is a left-side elevational view thereof;

FIG. 5 is a right-side elevational view thereof;

FIG. 6 is a top plan view thereof;

FIG. 7 is a bottom plan view thereof;

FIG. 8 is a rear, right-side, bottom perspective view thereof; and,

FIG. 9 is a reference view showing the resistor in a state of use.

The broken lines in the drawings illustrate environment and portions of the resistor that form no part of the claimed design.

1 Claim, 5 Drawing Sheets
